MULTIPLE WEDGING TOOL ASSEMBLY

Henry M. Sheridan, Painesville, Ohio, assignor to
The Apex Tool & Cutter Company, Inc., a cor-
poration of Connecticut

Application March 22, 1938, Serial No. 197,421

2 Claims. (Cl. 29—105)

The present invention relates to improvements in means for locking the blade or blades of inserted blade cutting-tools firmly and securely in the body holder or member. It has for its primary object to provide a blade lock for the blades of a cutting-tool such as rotary cutter or lathe tool in such manner as to eliminate auxiliary locking devices, e. g., pins, set screws etc., and their attendant disadvantages without a sacrifice to strength or rigidity in the assembled tool.

In view of the extreme amount of wear to which tools of this type are subjected, it has been found practical to make the cutting blades removable from the main supporting structure upon which they are carried. The blades, by being thus removable, may be replaced by new blades or may be re-sharpened in an adjusted position to maintain the original overall dimension of the cutting-tool. Also by making the blades separate from the supporting body member, the materials may be economically and efficiently used in accordance with the functions to be performed by the various elements of the cutting-tool. The modern cutting-tool of the type disclosed herein ordinarily includes a body portion made of mild steel, which is strong and tough and comparatively inexpensive. The inserted teeth, however, are of an entirely different material and are designed to resist the wear and strains to which they are subjected by being brought into contact with the part to be machined. Such blades are, therefore, usually made of what is known as "high speed steel" and the material therein is much more expensive than the material in the body portion.

One of the essential objects of the invention is to provide a cutting-tool wherein the cutting elements are capable of being adjusted with respect to the body of the tool and may be readily and positively held immovable in such adjusted positions.

For a consideration of what I believe to be novel and my invention, attention is directed to the following description and claims in connection with the attached drawing.

Figure 1 is a side view in elevation of a rotary cutter showing the cutting blades assembled therein.

Figure 2 is an end elevation thereof looking from the right in Figure 1.

Figure 3 is an enlarged side elevation of one of the blades and its locking wedge showing more clearly their relative position as assembled in the cutter.

Figure 4 is an end elevation of Figure 3.

Figure 5 is an elevation of the opposite side of the blade shown in Figure 3.

Figure 6 is an end elevation of the blade and wedge shown in Figure 5;

Figure 7 is a top plan of the blade and wedge shown in Figure 3; and

Figure 8 is a bottom plan of the blade and wedge shown in Figure 5.

The present invention is characterized by a 10 blade, a wedge and a blade and wedge slot, the coacting surfaces of which are so slanted as to provide multiple wedging action so as to secure the blade against movement with respect to its holder. Serrations may be provided between the 15 coacting surfaces to provide an enhanced secured relation therebetween.

By referring to the drawing, the numeral 10 represents a tool holding body of the milling cutter type, although the invention is not specifically 20 confined to such holders. The body 10 is provided with a plurality of radial tool and wedge receiving apertures each of which have both side walls slanted outwardly from each other from the periphery inward, thus to form a slot of greater 25 width at the bottom than at the periphery. The slots are shown as having a center line at an angle from a radius of the cutter and such an angle may be omitted or may vary with specific choice of the manufacturer. The side walls of 30 the slot also diverge, the rear side of the slot being narrower than the front or cutting side. Thus a cross-section transverse of the slot will render a plane, the ends of which are not parallel, and no two such cross-sections will be of 35 equal length. Thus the slot may be described as tapering outwardly, at the bottom, and outwardly towards the front.

The cutter blade is indicated by the numeral 11 and may be described as partaking of one- 40 half of the radial slanting characteristics of the slot. That is, the side wall, which will engage the side wall of the slot, is slanted outwardly towards the bottom and is parallel transversely with its opposite side wall. The opposite side is 45 parallel with a plane taken perpendicularly through the center of the slot and does not partake of the vertical slant of either side wall. Since the outer cutting edge of the top of the cutter is bevelled to provide a clearance angle, 50 any cross-section through the cutter will depict a plane, two sides only of which are parallel and no two horizontal sections will be equal.

A wedge 12 is of similar but of opposite configuration with respect to the radial wedge section 55

of the cutter 12. In addition, its outer face, which contacts the aperture wall, is slanted both vertically and transversely to conform thereto, but its inner face is, as is the inner face of the cutter, parallel to a plane passing through the center of the aperture. Its cross-sectional characteristics are thus similar to those of the cutter.

The coacting surfaces of the cutter and aperture are shown as vertically serrated, not only to insure their securement but also to provide a step-by-step transverse adjustment of the blade with respect to the holder. The coacting surfaces between the cutter and wedge are also preferably serrated, or roughened, to insure frictional locking therebetween. If desired, the coacting surfaces between the wedge and the slot could also be serrated.

As indicated in the drawings, the blade and wedge are assembled with their larger edges downward in the slot, thus to combine to fill the tapering slot and thus to preclude outward movement therefrom. They are further assembled with their thinner ends rearwardly of the slot so they combine also to form a joint rearwardly tapering assembly conforming to the rearward taper of the slot.

To those skilled in the art, it will be seen that, by driving in the wedge, the tapers of the various surfaces interlock to preclude movement of the blade in any direction. Since serrations between blade and aperture are vertical, transverse movement is precluded and the wedging construction precludes outward movement.

In accordance with the provisions of the patent statutes, I have described the principle of my invention, together with the apparatus which

I now consider to represent the best embodiment for carrying out my invention, but I desire to have it understood that the apparatus, as shown, is only illustrative thereof and that changes may be made without departing from the scope of my invention.

What I claim as new and desire to secure by Letters Patent of the United States is:

1. In a multibladed milling cutter, a rotary body having a plurality of peripheral tool and wedge receiving apertures, the bottom of each of which lies at an angle to the axis of the cutter body and which are of greater width at the bottom than at the outer edge and of greater width at one transverse end than at another and tool and wedge assemblies therein, comprising a tapered tool and a tapered wedge their compound cross-section conforming to the cross-section of the apertures both vertically and transversely, the cooperating surfaces of the tool and aperture having serrations thereon.

2. In a multibladed milling cutter, a rotary body having a plurality of peripheral tool and wedge receiving apertures, the bottom of each of which lies at an angle to the axis of the cutter body and which are of greater width at the bottom than at the outer edge and of greater width at one transverse end than at another and tool and wedge assemblies therein, comprising a tapered tool and a tapered wedge their compound cross-section conforming to the cross-section of the apertures both vertically and transversely, the cooperating surfaces of the tool and aperture having vertical serrations thereon.

HENRY M. SHERIDAN.
